Primary Examiner — Bridget L Eland(74) *Attorney, Agent, or Firm* — Banner & Witcoff, Ltd.**CLAIM**

The ornamental design for a handset keypad, as shown and described.

DESCRIPTION

FIG. 1 is a perspective front view of a handset keypad showing our new design;

FIG. 2 is a front view thereof;

FIG. 3 is a right side view thereof; and,

FIG. 4 is a left side view thereof.

The broken line showing of the environmental structure of the handset is for environmental purposes only and forms no part of the claimed design.
